UNITED STATES PATENT OFFICE

2,553,864

FOWL MATING SADDLE

Clarence L. Neely, Corydon, Iowa

Application April 11, 1949, Serial No. 86,828

8 Claims. (Cl. 119—143)

1

The principal object of my invention is to provide a protective covering for the back of female fowls which is easily and quickly attached or detached and which serves to prevent the fowl from being scratched or torn in mating.

A further object of this invention is to provide a protective covering for the back of a female fowl for use during the mating process, which covering will fit snugly to the fowl and is prevented from slipping, becoming loose or accidentally detached by a locking means on each of the wing straps.

A still further object of my invention is to provide a protective covering as set forth above which is free from metal parts of any kind, such as hooks, snaps or buckles.

A still further object of this invention is to provide a protective covering or saddle for the back of a female fowl that will cause a minimum of irritation to said fowl but which will remain firmly attached thereto, even during windy days.

A still further object of my invention is to provide a protective covering for the back of a female fowl for use during the mating process, which covering provides toe-hold and traction straps for the male.

A still further object of this invention is to provide a protective covering for female fowls that is economical in manufacture and durable enough to be usable for several seasons.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawings, in which:

Fig. 1 is a top plan view of my fowl saddle.

Fig. 2 is a bottom plan view of my fowl saddle.

Fig. 3 is an enlarged side view of my invention taken from the line 3—3 of Fig. 1.

Fig. 4 is an enlarged side view of a portion of my device, illustrated similarly to Fig. 3, and shows parts thereof in open position.

Fig. 5 is an enlarged cross-sectional view of my device taken on the line 5—5 of Fig. 1.

Fig. 6 is a top plan view of my invention in place on the back of a female fowl.

A serious problem in the commercial raising of fowl such as turkeys is the fact that hens are frequently scratched and torn both in body and feather by the male during the mating process with a resultant loss in revenues from the sale of said hens due to the fact that some hens so

2

injured die and others are graded down commercially so as to bring in less revenue than those not so injured. Some attempts to overcome this have been made by the use of coverings or saddles but such attempts have not been entirely successful because of the difficulty involved in attaching and detaching such saddles, and for the further reasons that saddles now in use have a tendency to become loosened or detached, do not fit snugly and properly and therefore cause considerable irritation and damage to the fowl by rubbing. I have overcome these objections as will hereinafter be appreciated.

Referring to the drawings I have used the numeral 10 to designate a flat circular turtle shaped covering. This may be made from any durable material such as duck, canvas or the like. The sides are rounded and the front forward edge is provided with three arcs or concave portions 12, 13 and 14, as shown in Fig. 1 and Fig. 2, the center arc 13 fitting around the back of the neck and the side arcs 12 and 14 fitting around the left and right wing respectively of a female fowl, as shown in Fig. 6. The rear end of the covering is straight. The entire marginal edge of the covering 10 is turned under toward the underside sufficiently to allow it to be double stitched. The purpose of this double stitching is to do away with any tape or binding that might come loose and cause the fowl to become tangled up therein. On the outer or top side of the covering 10 there are placed two back straps 18 and 19 for the left and right side respectively and two wing straps 20 and 21 for the left and right side respectively. These straps may be made from any durable material and the back and wing strap for each respective side, 18 and 20 for the left and 19 and 21 for the right, is made from one continuous piece of material which is formed by folding one half of the material used back upon the other half so as to make a strap of two thicknesses of said material. The left back strap 18 extends from a rear point, left of center on the top of the covering 10 forwardly and inwardly so as to bisect the forward point of covering 10 between arcs 12 and 13, as shown in Fig. 1. The wing strap 20 extends forwardly, outwardly and rearwardly in an arc to form an enclosed space between itself and arc 12. It then passes through a loop 22 located on the left forward side of the covering 10, then continuing parallel and adjacent to the underside of the outer edge of the left side of covering 10 where it is bar-tacked thereto at a side point substantially midway between the rear and front end of said covering, as shown in Fig. 2.

The right back strap 18 extends from a rear point right of center on the top of the covering 10 forwardly and inwardly so as to bisect the forward point on covering 10 between arcs 13 and 14. The wing strap 21 continues forwardly, outwardly and then rearwardly in an arc in the same manner as described for the left back wing strap 20. It is attached to the right center side of covering 10 in a like manner as the wing strap 20 after loosely passing through its loop 22 located at the right side edge of the covering. In placing these two tube loops 22, I recommend that they be positioned just to the rear of the two concave portions 12 and 14 of the covering. The back straps 18 and 19 are double stitched throughout their entire length to covering 10. The double thickness of the left wing strap 20 which is an extension of the double thickness back strap 18 is stitched together only at the bottom or open edges of the double thickness from a point where it extends upwardly and outwardly from covering 10 to where it is tacked to the side of covering 10, and the right wing strap 21 is stitched in a like manner. The purpose of this stitching on only one edge is to provide a cushion on the top edge of said wing straps 20 and 21 that will eliminate chafed wings. The small loops 22 through which the wing straps 20 and 21 pass may be made from the same material as the back straps 18 and 19 and are formed by folding half of a short length of said material back upon itself with one end placed on the top side of covering 10 and one end on the underside of covering 10 and stitching the three surfaces together, as shown in Fig. 5. The loops 22 should be large enough to allow free passage of the wing straps 20 and 21, but not large enough to allow free and easy passage of said wing straps when an extra thickness of strap of like material is added to the rear thereof, and which will now be described. On the left wing strap 20 between the point where said strap is tacked to the underside of the covering 10 and forwardly to loop 22 and on the underside of said wing strap 20 there is placed another section of strap 24 which is bar-tacked at its extremities to the wing strap 20, as shown in Fig. 3. This additional strap 24 may be made from the same material as the wing strap 20. The purpose of this additional strap 24 is to provide an extra thickness for that portion of the wing strap 20 between the loop 22 and the tacked end of said strap, as shown in Fig. 3, and thereby creating a locking device on the wing strap 20 due to the fact that the portion of the wing strap 20 having said multiple thickness will not freely move upwards through the loop 22 and thereby locks in place the wing strap 20 after it is attached and prevents it from becoming loose. The right wing strap 21 is provided with an extra thickness of material 24 in the same manner and fashion as above described for the left wing strap 20. On the top side of covering 10 there has been placed two additional transverse straps between the back straps 18 and 19. One of said additional straps 25 is placed near the top of covering 10 and the other 26 near the bottom of said covering 10, as shown in Fig. 1. These straps 25 and 26 are double-stitched to covering 10 and serve not only as a reinforcement for the saddle but also as a non-slip toe-hold and traction strap for the male.

This saddle has no snaps, buckles or metal parts to engage or disengage in either attaching or detaching and is easily used as follows:

To prepare the saddle for attaching, the loops 22 are manually spread open and that portion

of the wing straps 20 and 21 having attached thereto the extra thickness of the straps 24 are pushed or pulled forwardly through the loops 22 until the rear tacked ends of said wing straps approach the loops 22, as shown in Fig. 4. This will enlarge the enclosure formed by wing strap 20 and arc 12 and the enclosure formed by wing strap 21 and the arc 14, thereby making it easy to slip the wings of the fowl through the respective collars formed by the wing straps and the respective arcs. Once the wing straps are in place around the wings, the wing straps 20 and 21 are drawn rearwardly through the loops 22 to their original position, as shown in Fig. 3 and are automatically locked in place since the multiple thickness of said straps will not normally pass through the loops 22 without using an applied force to enlarge said loop 22 and draw the straps forwardly. The saddle is easily attached by enlarging the size of the areas enclosing the wings in the same manner as for attaching. The portions 24 act as latch means for preventing the slipping action of the wing straps forwardly through the loops 22 except when manually manipulated. Also the flexible stiffness of the covering aids in holding the wing straps rearwardly against accidental forward slipping movement. The rear end of the cover 10 is cut substantially straight across, as shown in Fig. 2, so as not to interfere with the breeding of the female fowl. While I have described the various straps 18, 19, 20, 21, 22, and 24 as made of strip material folded back upon itself to provide a strap of two thicknesses, it is obvious that such straps may be made by several folds to produce a multiplicity of layers or fold thicknesses. These straps may be made of any suitable flexible material.

Some changes may be made in the construction and arrangement of my fowl mating saddle without departing from the real spirit and purpose of my invention, and it is my intention to cover by my claims, any modified forms of structure or use of mechanical equivalents which may be reasonably included within their scope.

I claim:

1. In a fowl saddle, a flexible sheet member, a forwardly positioned loop member secured to each side portion of said flexible sheet member, two spaced apart wing straps each secured at its inner end to the forward end of said flexible sheet member, one of said wing straps extending forwardly, to the left and then rearwardly to pass through one of said loops and the other said wing strap extending forwardly to the right, and then rearwardly to pass through the other said loop, and a means for securing the outer ends of each of said wing straps to said flexible sheet member at a point substantially rearward of the loop through which it passes.
2. In a fowl saddle, a flexible sheet member, a forwardly positioned loop member secured to each side portion of said flexible sheet member, two spaced apart wing straps each secured at its inner end to the forward end of said flexible sheet member, one of said wing straps extending forwardly, to the left and then rearwardly to pass through one of said loops and the other said wing strap extending forwardly, to the right, and then rearwardly to pass through the other said loop, a means for securing the outer ends of each of said wing straps to said flexible sheet member at a point substantially rearward of the loop through which it passes, and a latch means on each of said wing straps for preventing the

accidental forward sliding of the strap in the loop that embraces it.

3. In a fowl saddle, a flexible sheet member, a forwardly positioned loop member secured to each side portion of said flexible sheet member, two spaced apart wing straps each secured at its inner end to the forward end of said flexible sheet member, one of said wing straps extending forwardly, to the left and then rearwardly to pass through one of said loops and the other said wing strap extending forwardly, to the right, and then rearwardly to pass through the other said loop, a means for securing the outer ends of each of said wing straps to said flexible sheet member at a point substantially rearward of the loop through which it passes, and a means for increasing the thickness of each of said wing straps just rear of the loop that embraces it.

4. In a fowl saddle, a flexible sheet member, a forwardly positioned loop member secured to each side portion of said flexible sheet member, two spaced apart wing straps each secured at its inner end to the forward end of said flexible sheet member, one of said wing straps extending forwardly, to the left and then rearwardly to pass through one of said loops and the other said wing strap extending forwardly, to the right, and then rearwardly to pass through the other said loop, a means for securing the outer ends of each of said wing straps to said flexible sheet member at a point substantially rearward of the loop through which it passes, and a means for increasing the thickness of each of said wing straps just rear of the loop that embraces it; said flexible sheet member, loops, and wing straps being of substantially the same flexible material.

5. In a fowl saddle, a flexible sheet member, a forwardly positioned loop member secured to each side portion of said flexible sheet member, two spaced apart wing straps each secured at its inner end to the forward end of said flexible sheet member, one of said wing straps extending forwardly, to the left, and then rearwardly to pass through one of said loops and the other said wing strap extending forwardly, to the right, and then rearwardly to pass through the other said loop, a means for securing the outer ends of each of said wing straps to said flexible sheet member at a point substantially rearward of the loop through which it passes; said wing straps each being constructed of a single strip of flexible material folded back upon itself along its longitudinal axis with its side edges extending away from the wings of the fowl user, and stitching at the outer side edges of each of the straps whereby the folded unstitched side of each of said straps forms a cushioned strap portion to prevent chafing of the fowl.

6. In a fowl saddle, a flexible sheet member provided with a centrally located concave forward edge and a concave edge at each side of said centrally located concave edge, a loop member secured to each flexible sheet member adjacent the outer edge of each of said concave edge portions that reside at the side of said centrally located concave edge portion, two wing straps secured to the forward end of said flexible sheet

member adjacent each side of said centrally located concave edge respectively; one of said wing straps extending forwardly, to the left and then rearwardly to pass through one of said loops and the other said wing strap extending forwardly, to the right, and then rearwardly to pass through the other said loop, and a means for securing the outer ends of each of said wing straps to said flexible sheet member at a point substantially rearward of the loop through which it passes; said wing straps each being constructed of a single strip of flexible material folded back upon itself along its longitudinal axis with its side edges extending away from the wings of the fowl user, and said side edges secured together whereby the folded unstitched side of each of said straps forms a cushioned strap portion to prevent chafing of the fowl.

7. In a fowl saddle, a flexible sheet member, 20 a forwardly positioned loop member secured to each side of said flexible sheet member, two spaced apart straps secured across the longitudinal top of said flexible sheet member thence forward of the front end of said flexible member 25 to form wing straps; one of said wing straps extending forwardly, to the left and then rearwardly to pass through one of said loops and the other said wing strap extending forwardly, to the right, and then rearwardly to pass through 30 the other said loop, and a means for securing the outer ends of each of said wing straps to said flexible sheet member at a point substantially rearward of the loop through which it passes.

8. In a fowl saddle, a flexible sheet member, a forwardly positioned loop member secured to each side of said flexible sheet member, two spaced apart straps secured across the longitudinal top of said flexible sheet member thence 40 forward of the front end of said flexible member to form wing straps; one of said wing straps extending forwardly, to the left and then rearwardly to pass through one of said loops and the other said wing strap extending forwardly, to the right, and then rearwardly to pass through 45 the other said loop; each of said straps forwardly of said flexible member being folded back upon itself along its longitudinal axis and having its side edges stitched together whereby the folded 50 unstitched side of each of said straps forms a cushioned strap portion to prevent chafing of the fowl, a means for securing the outer ends of each of said wing straps to said flexible sheet member at a point substantially rearward of the loop through which it passes, and a strap member secured on the top of said flexible sheet member extending transversely of its longitudinal length.
